UNITED STATES PATENT OFFICE.

GEORGE A. DOERR, OF PEORIA, ILLINOIS.

WATER-COOLER.

1,390,280.

Specification of Letters Patent. Patented Sept. 13, 1921,

Application filed February 3, 1919. Serial No. 274,601.

To all whom it may concern:

Be it known that I, GEORGE A. DOERR, citizen of the United States, residing at Peoria, in the county of Peoria and State of Illinois, have invented certain new and useful Improvements in Water-Coolers; and I do hereby declare that the following is a full, clear, and exact description of the invention, which will enable others skilled in the art to which it appertains to make and use the same.

This invention relates to improvements in water-coolers for internal combustion engines. It relates more particularly, however to improvements in radiators of the portable type or those mounted upon tractors, trucks and other forms of gas propelled vehicles.

The main object of the invention is to construct a radiator so that the water to be cooled will flow through a series of spaced receptacles, one above another, having bottoms composed of foraminous material, and that in the passage from one to another the water will descend through the air in a finely divided form so as to be very rapidly cooled.

Another object of the invention is to construct a radiator wherein the water will be so rapidly cooled that the loss thereof due to vaporization will be reduced to a minimum.

Still another object is to provide a type of radiator that will be simple in construction, that can be produced at a comparatively low cost, and that can be readily repaired by an inexperienced person in but a short time at small expense.

Still another object is the provision of a structure in a radiator in which the parts can be mainly produced from dies and readily and quickly assembled.

Other objects and advantages will appear as the description of the invention proceeds, aided by the accompanying drawing where-
in:

Figure 1 is a side elevation of a radiator constructed according to my invention.

Fig. 2 is an end elevation thereof.

Fig. 3 shows a receptacle in perspective.

Fig. 4 is a transverse sectional elevation of part of what is shown in Fig. 2, and

Fig. 5 shows in perspective a modified form of a spraying device.

The types of radiators commonly used are expensive both by reason of the manner of their construction and the work necessary

to produce them. Further than this the radiators, particularly those used on tractors, do not cool the water quickly enough to prevent rapid vaporization often causing considerable inconvenience.

My radiator is designed to keep the water properly cooled under the most exacting conditions.

1 indicates a tank large enough to contain the amount of water to be used in the radiator. Secured to each of its ends is a pair of upstanding angle bars 2 between which is held a hood spaced above said tank comprising end portions 3, for example, bolted to said angle bars, and the sides and top portion 4 and 5 respectively, while 2' indicates a pair of bars secured to the top of the said tank 1 for supporting the whole structure upon the vehicle with which it is used.

Stationed between the tank 1 and said hood is a series of hopper-like trays 6 whose walls are preferably straight forming rectangular trays spaced from one another, the lower portion of one depending well down into the other as clearly shown in Fig. 1, the areas of their lower portions being less than their upper portions.

Each is provided with a bottom of foraminous material 7 such as wire screen or perforated metal, or other suitable material, which may be attached thereto but preferably in such a way as to be easily removed.

The lowermost tray of the series may or may not be provided with the screen but in any event it is secured to the top of the tank 1 in a water-tight manner, the latter having an opening 8 in its otherwise closed top for receiving all of the water from the said series of members, and any means may be employed to prevent the water from slopping over the sides of the said lowermost member if, indeed, it is found necessary.

9 indicates an outlet in the side of the tank for the water. 9' is indicative of any suitable pumping means for elevating the water from said tank and discharging it inside the hood through a pipe 10. The water thus introduced is preferably sprayed throughout the hood so as to break it up thoroughly before beginning its descent through the several trays 6.

Two methods of accomplishing this spraying are shown herein although there are other ways open for use not necessary to describe.

In Figs. 2 and 4, for example, is shown a

stand-pipe 11 which in this instance serves two purposes. Its use in connection with the spraying will first be described. It stands opposite the discharge end of the pipe 10 and is indented at 12 as shown.

5 The water is forced upon or into such indentation and is caused to be thrown violently in all directions upon the walls of the hood thence descending by gravity through

10 the several trays 6 and their bottoms 7.

In Fig. 5 another method is shown. The discharge pipe in this case is denoted by 13 and enters the top of the hood. Beneath its discharge opening is a deflector 13' of any 15 desired form, suitably supported, upon which the flow of water is discharged to obtain the required or desired spraying action.

The stand-pipe 11 in the first described 20 form of the apparatus is employed for spraying purposes only as a convenience and in the absence of a special deflector. Its real or main purpose is that of assisting in cooling the water. As shown in Figs. 1 and 2 it extends from close to the top of the tank

25 1 up to, and opens out through the top of the hood. The lower end is provided with a small opening 14, Fig. 4, and at intervals throughout its length is furnished with slits 15 between the bottoms of the trays 6.

30 16 indicates an exhaust pipe from the engine, not shown, which pipe enters the stand-pipe 11 and turns upwardly into a nozzle within the same.

In action, the water as sprayed within 35 the hood 3, 4, 5 falls upon the foraminous bottom of the uppermost tray 6 and in its passage therethrough is finely divided, passing successively through the other bottoms of the members 6 lower down until it finally 40 enters the tank or receptacle 1 from which it is returned to the hood by the pump keeping up a continuous flow.

The water in its finely divided form in its descent is exposed to the air which has free 45 access to the interior between the trays 6, and the entrance of the air thereto is aided by the forced air currents in the stand-pipe. That is to say, the exhaust from the upturned end of the pipe 16 acts on the injector 50 principle and creates a strong upward air current in the said stand-pipe drawing in air through the slits 15. This, of course draws air inwardly between the trays 6 which in meeting the descending water in its broken 55 up form, as it passes from top to bottom of the radiator, acts to rapidly cool it.

Through the opening 14 of the stand pipe 11 the draft withdraws more or less of the vapors and heat from the tank 1.

60 The walls of the hood 3, 4, 5 prevent loss of the water being sprayed and in order to prevent splashing of water over the sides of the uppermost tray 6, in striking the bottom 7, a hinged lid 17 is provided at each side of

65 the hood to cover the opening at each side

as most clearly shown in Fig. 5. These lids are perforated so that air may enter and circulate beneath the hood to assist in cooling.

The form of arrangement shown in Fig. 5 70 last referred to does not show the stand-pipe 11 which pipe need not be used though preferable as aiding faster reduction of heat.

It is now to be noted that by providing a series of spaced diaphragms such as 7 of 75 foraminous material the water in its fall is again and again broken up into such fine form that all of it is exposed to the air in that form time and again, besides which, the material of which the several trays 6 and 80 their bottoms 7 may be made will rapidly radiate the heat, by being separated from one another, and quickly remove the heat from the water that falls upon them.

The cooling action is particularly rapid, 85 of course, when the radiator is carried upon a tractor, truck, pleasure car, or other moving body because of the forced movement of the air therethrough.

I am aware that an exhaust pipe has been 90 erected within a radiator for assisting in cooling the water but it has not been applied in the manner herein shown and described.

Further, I am aware that a pumping device 95 is not new in a radiator except in combination with the structure herein.

Since the radiator is of open form throughout, any part may be readily reached for insertion or removal of bolts or the like, and 100 any other part may be removed or replaced without disturbing others. The spacing of the trays 6 may be such that any one of them may be readily extracted by removing the bolts that secure it to the angle bars 2, 105 all of which will be understood.

I may make such changes in the construction of my apparatus as may be considered within the invention and the scope of the 110 accompanying claims.

My construction is such as to be peculiarly fitted as a portable radiator or one for use upon motor vehicles, especially tractors, the trays 6 being dropped into one another far enough to prevent loss of water either by 115 splashing or "slopping" as the vehicle rocks and rolls.

Though not shown, the pipe 16 may be covered with asbestos or other suitable material, or may be otherwise protected so that 120 it will not heat the air in the hood nor tend to heat the water falling toward or around it.

I claim:

1. A radiator for internal combustion engines including in its construction a series 125 of separate water-receiving hopper-like trays each having a bottom of foraminous material, the trays being spaced one above another, their bottoms depending well down within adjacent trays, a structure for sup- 130

porting the trays, a receptacle for water below the series of trays, a pumping device connected with the receptacle, and a conduit connected with the pump terminating above the series of trays for discharging water into the same.

2. A radiator for internal combustion engines including in its construction a series of separate water-receiving hopper-like trays each having a bottom of foraminous material, the trays being spaced one above another, their bottoms depending well down within adjacent trays, a structure for supporting the trays, a receptacle for water below the series of trays, a pumping device connected with the receptacle, a conduit connected with the pumping device and terminating above the series of trays for discharging water into the same, and an open conduit erected in the series of trays extending through their bottoms and having openings therein within the several trays and also having an opening in its lower end.

3. A radiator for internal combustion engines including in its construction a series of separate water-receiving hopper-like trays each having a bottom of foraminous material, the trays being spaced one above another, their bottoms depending well down within one another, a structure for supporting the trays, a receptacle for water below the series of trays, a pumping device connected with the receptacle, a conduit connected with the pumping device and terminating above the series of trays for discharging water into the same, a second open conduit erected in the series of trays extending through their bottoms and having openings therein within the several trays, the last named conduit having an opening at its lower end, said end being in spaced relation to the said receptacle, and means separate from the last named conduit and from the trays for spraying water discharged from the first mentioned conduit.

4. A radiator for internal combustion engines including in its construction a series of separate hopper-like trays for receiving a medium to be cooled, spaced one above another and each having a bottom of foraminous material the bottom of one depending well into another, a receptacle below the members, a hood surmounting the said series of members including a deflector therein, a pipe having an opening disposed opposite the deflector, and means to elevate the said medium to be cooled from the receptacle through said pipe, said pipe being positioned so as to direct the said medium against said deflector.

5. A radiator for internal combustion engines including in its construction a series of hopper-like trays spaced above one another

for receiving a medium to be cooled, each having a foraminous bottom, the several trays extending well down into one another, 65 a receptacle below the series of receiving trays, having an opening in its top, a stand-pipe extending up through the trays and their bottoms provided with openings at intervals throughout a part of its length, 70 the lower end of said pipe terminating substantially at the opening of said receptacle and provided with an opening, a pumping device connected with the receiver, and a conduit connected with the pumping device 75 and terminating above the series of trays for supplying water to the same.

6. A radiator for internal combustion engines including in its construction a receptacle, upstanding supports secured 80 thereto, a hood secured between the upper portions of the supports spaced from said receptacle, and a series of spaced receiving trays mounted in the supports having perforated bottoms and disposed between the 85 receptacle and the hood, said trays depending into one another, and a conduit connected with the receptacle and terminating above the said series of members within the hood, and water means connected with said conduit for elevating water from the receptacle 90 into said hood.

7. A radiator for internal combustion engines including in its construction a series of separate water-receiving hopper-like trays 95 having foraminous bottoms and spaced from one another, a cover for the topmost tray including a foraminous hinged portion, a receptacle for water disposed beneath the series of trays, a conduit for supplying water 100 terminating above and for discharging into the topmost tray, and means to elevate the water from the receptacle therethrough.

8. A radiator for internal combustion engines including in its construction a receptacle for water, a series of spaced trays above the same, supports affixed to the receptacle and having the trays secured thereto, the latter depending into one another and having perforate bottoms, a pumping device connected with the receptacle, a pipe connected to the device and terminating above the series of trays supplying water to the latter, a hood mounted above the said series of trays and inclosing the top of the 110 uppermost of said trays, the said pipe extending into the same, said hood having a movable perforated closure as a part thereof.

In testimony whereof I affix my signature in presence of two witnesses.
